UNITED STATES PATENT OFFICE.

FRANK C. ROBERTS, OF NASHVILLE, TENNESSEE.

DESIGN FOR A COMBINED HAT-RACK AND UMBRELLA-STAND.

44,711.

Specification for Design.

Patented Sept. 30, 1913.

Application filed July 19, 1913. Serial No. 780,076. Term of patent 14 years.

To all whom it may concern:

Be it known that I, FRANK C. ROBERTS, a citizen of the United States, residing at Nashville, in the county of Davidson and State of Tennessee, have invented a new, original, and ornamental Design for a Combined Hat-Rack and Umbrella-Stand, of which the following is a specification, reference being had to the accompanying drawing, forming part thereof.

The figure is a perspective view, showing my new design.

I claim:

The ornamental design for a combined hat rack and umbrella stand, as shown.

FRANK C. ROBERTS.

Witnesses:

THOS. CRUNISS,
JOHN F. GAFFNEY.
